UNITED STATES PATENT OFFICE.

WILLIAM F. ZIMMERMANN, OF MAPLEWOOD, NEW JERSEY, ASSIGNOR TO GOULD & EBERHARDT, OF NEWARK, NEW JERSEY, A CORPORATION OF NEW JERSEY.

ADJUSTABLE SPINDLE BEARING FOR HOBBING MACHINES.

Application filed March 13, 1925. Serial No. 15,218.

This invention is devoted to precision machines for accurately hobbing superior gears. When gears are formed by the progressive action of a helicoidal cutter, the resultant motion is a mathematical complex of three simultaneous component motions; to wit, a rotation of the cutter about its own axis, a rotation of the blank about its own axis, and a translation between the cutter and the blank. The coordination is very involved and must be exactly maintained because any irregularity in any one of the component motions will disproportionately influence the others and the ultimate relativity will be unduly distorted and an unprecise product will be generated.

Any side-play of the cutter in the direction of its axis will introduce a disarrangement into the rotation of the work relative to the cutter; any dislocation of the axis of the cutter toward or away from the axis of the blank, or any converse dislocation of the axis of the work, will cause a departure from the true depth of tooth; any deviation from a straight-line translation in the feed or bodily travel of the cutter will create a complex error in the generation of the tooth curves, etc.

Nor does it suffice to depend upon an initially correct setting of a structurally accurate machine by reason of the fact that the metals employed have different coefficients of expansion and because temperature variations are created, during the period of operation, by the friction of bearings and the working of the cutter. It follows that a bearing, which is not too loose at the beginning, would become too tight after the parts have warmed up to the conditions of normal running. To meet this contingency and enable the intrinsic accuracy of the machine to be uniformly maintained, the mechanism should be constructed to afford its user full convenience and facility in effecting compensation during the working period; it being especially essential that such adjustments may be made in an evenly progressive manner and without any preliminary derangement of the mounting.

Not only is it important that the machine should embody compensative means, as aforesaid, but it is also consequential that its mechanical arrangement should be such as to reduce to a minimum the occasions for ma-

nipulating such means. For example, its structure should be such that expansions (which are unavoidably caused by the heat) will be accommodated in a manner least able to influence unfavorably the correct relativity of the working elements.

How these objectives may be attained, will now be explained in the following specification of a concrete example of the invention; reference being had to the drawings of which:—

In the accompanying drawings, Fig. 1 is an assembly view of the work spindle and the cutter spindle with the inter-connecting gearing. Fig. 2 is a sectional elevational view of the work spindle. Fig. 3 is a section along the line 3—3 of Fig. 2. Fig. 4 is an elevational view of the cutter carriage and the cutter spindle mounted thereon. Fig. 5 is a section along the line 5—5 of Fig. 4. Fig. 6 is an end elevational view of the cutter carriage and Fig. 7 is a section along the line 7—7 of Fig. 4.

Referring to the accompanying drawings and particularly to the assembly view shown in Fig. 1, a cutter spindle 1, which carries a suitable cutter or hob 2, is rotated and given a movement of translation with respect to the work which is carried by a work spindle 3. The work spindle 3 and the cutter spindle 1 must be rotated at a predetermined ratio with respect to each other and moreover the hob 2 and the work must be positioned in exact relation with respect to each other. The cutter spindle 1 is operated by means of a worm gear wheel 4 which meshes with a worm 5. The worm 5 has a splined connection with a shaft 6 in order to permit vertical movement of the cutter spindle 1, the worm wheel 4 and the worm 5, in accordance with the rotation of the cutter spindle. The spline shaft 6 carries a bevel gear wheel 7 which meshes with a bevel gear wheel 8 on a shaft 9. The shaft 9 carries a bevel gear wheel 10 which meshes with a bevel gear 11 on a shaft 12. The shaft 12 is connected by spur gear wheels 13 and 14 to a main driving shaft 15.

The shaft 9, which carries the bevel gear wheels 8 and 10, also carries a pinion 16 which meshes with a gear wheel 17 on the shaft 18. The shaft 18 carries a worm member 19 which operates a worm wheel 20 on the work spindle 3. By means of such gear-

ing, as above set forth, the cutter spindle 1 and the work spindle 3 are rotated in correct relation with respect to each other.

It is not only necessary to effect the movement of translation and rotation of the cutter spindle 1 in exact relation with respect to the rotation of the work spindle 3 but it is also necessary to support the two spindles 1 and 3 in bearings so as to prevent any movement therein other than what has been determined. The cutter spindle 1 is supported in bearings 21 and 22 which must insure against any casual movement by the spindle during the cutting operation. Moreover, the bearings must be adjustable as to the diameter of the spindle and accurately fit the spindle under cutting conditions. It should be noted that during the operation of the hobbing machine, the spindle 1 tends to become hot inasmuch as the bearings 21 and 22 must be snugly fitted thereto. The heating of the spindle causes it to enlarge as well as to expand axially and interfere with the axial adjustment of the spindle with respect to one of the bearings. Provision is made in a hobbing machine constructed in accordance with my invention to insure against inaccurate work when the spindle is elongated by heat. A full description of the adjustment for the bearings 21 and 22 will be given when reference is made to Figs. 4, 5, 6 and 7 of the drawings.

Referring to Figs. 2 and 3 of the drawings, the work spindle 3 is shown supported by a bearing frame 23 which in turn is suitably connected to a frame 24. A work spindle bushing 25, which is preferably composed of bronze, is mounted within the bearing frame 23 and directly supports the work spindle 3. The bushing 25 has a cylindrical outside surface which is fitted to the bearing frame 23 and is provided with a conical inside surface which is fitted to a conical portion of a work spindle 3. The conical shape of the bearing surface between the spindle and the bushing permits the adjustment as to the diameter of the bushing with respect to the spindle. The head 26 of the work spindle engages an intermediate plate 27 which is secured to the top of the bearing frame 23. A suitable key member 28 is provided between the intermediate plate 27 and the bronze bushing 25 in order to prevent any rotation of the bushing in accordance with the movement of the spindle and a recess 29 is formed in the bearing frame 23 below the plate 27 for carrying an adjusting nut 30. The adjusting nut 30 is provided with threads which engage threads 31 on the bushing 25. Suitable worm teeth 32, which mesh with a worm 33, are formed on the outside of the nut. The worm 33 is formed on a shaft 34 which is supported in the bearing frame 23, as shown in Fig. 3 of the drawings. The end 35 of the shaft 34

is preferably shaped to receive a wrench to facilitate manual adjustment thereof and thereby effect a longitudinal adjustment of the bushing 25 within the bearing frame 23. In the above construction it is apparent rotation of the worm 33 and the nut 30 effect longitudinal movement of the bushing 25 irrespective of the operating condition of the work spindle 3. Thus, the adjustment of the bushing can be effected when the spindle 3 is in rotation.

A supporting plate 37, which is secured to the frame 24 by bolts 38, is provided for centralizing the bearing frame 23 at the lower end thereof. The worm wheel 20, which operates the work spindle, is mounted on the spindle 3 adjacent to the bearing frame 23, as shown in Fig. 2 of the drawings. A nut 39 is secured to the spindle 3 adjacent to the worm wheel 24 for controlling the end fit of the spindle within the bearing. In this regard it will be noted the nut 39 holds the head 26 of the spindle against the plate 27 and holds the worm wheel 20 against the end of the bearing frame 23. It should also be noted that the restriction of the spindle axially in the bearing is effected by an adjustable means which is separate and distinct from the means which adjusts the bearing with respect to the diameter of the spindle. Moreover, as above set forth, the adjustment of the bearing with respect to the diameter of the spindle may be effected while the spindle is rotating.

In many hobbing machines heretofore constructed the adjustment of the spindle as to end play and also the adjustment of the bearing with respect to the diameter of the spindle have been effected solely by means of a nut similar to the nut 39 which is secured to the end of the spindle. When two adjustments are effected by such nut, it is impossible to effect any adjustment of the bearing as to the diameter of the spindle when the spindle is rotating. Moreover, it is necessary to remove some of the metal beneath the head of the spindle whenever it is desired to adjust the position of the spindle bushing.

Referring to Figs. 4, 5, 6 and 7 of the drawings, the cutter spindle bearings 21 and 22 are shown supported on a carriage 40. The carriage 40 operates on suitable guide ways 41 and 42 which are a part of the upright stanchion 43. The carriage 40 is held in position on the guide ways by means of straps 44, as best shown in Fig. 5 of the drawings and suitable gibs 45 are associated with the straps 44. A vertical screw shaft 46 is provided for effecting vertical movement of the carriage 40 in timed relation to the rotation of the cutter spindle 1 and also in timed relation to the rotation of the work spindle 3. Inasmuch as my invention is not particularly related to the details of the power means for effecting vertical movement

of the carriage, it is deemed unnecessary to further describe it.

A plate 47, which is secured to the carriage 40 by means of bolts 40^a is provided with a semi-circular recess within which the bearings 21 and 22 are mounted. Provision is made, as will be hereinafter set forth, for effecting movement of the bearing 21 along the plate 47 for positioning the cutter spindle with respect to the work.

The bearing 21 comprises a bearing frame 49 which is directly secured to the plate 47 by means of straps 50 and bolts 51. A bushing 52, which is preferably composed of bronze, is provided in the bearing frame 49 for directly engaging the cutter spindle 1. The bronze bushing 52 has a cylindrical fit with the bearing frame 49 and a conical fit with the tapered section of the cutter spindle 1. The bronze bushing 52 is adjusted longitudinally to snugly fit the cutter spindle by means of a nut 53 which is constructed very similar to the nut 30 for adjusting the position of the bronze bushing surrounding the work spindle. The nut 53 is connected to the bushing 52 by means of screw threads 54 and is provided with gear teeth 55 for meshing with a pinion 56 on a short shaft 57. The shaft 57 is manually operated by means of a wrench applied to head 58, as shown in Fig. 5 of the drawings. Thus, by operating the shaft 57, the nut 53 is rotated for varying the longitudinal position of the bushing 52 within the bearing frame 49. The bushing 52 is prevented from rotating with the cutter spindle 1 by means of suitable member 59 which is splined thereto. The nut 53 is rotatably mounted in a recess 60 formed in the bearing frame 49 and is held in position by means of a retaining plate 61 which in turn is secured in position by means of a bolt 62.

A hardened steel plate 63 is secured to the one end of the bearing frame 49 by means of a screw 64 and a dust collar 65, as shown in Fig. 5 of the drawings, is held in position by the same screw 64. The dust collar 65 prevents any dust from entering the bearing so as to interfere with the bearing surfaces which prevent longitudinal movement of the cutter spindle with respect to the bearing. Although the dust collar 65 and the plate 63 are shown as separate members it is to be understood that if so desired such members may be formed integral with a recess therein for the spindle head 67. A washer 66, which is preferably composed of bronze material, is interposed between the head 67 of the cutter spindle 1 and the hardened plate 63. Another washer 68 which is preferably composed of bronze, is located between the hardened plate 63 and an adjusting nut 70. The washer 68 is held against rotation by means of a key member 69. The key member 69 prevents the washer

68 from rotating in order to insure against any relative rotation surface between it and the adjusting nut 70. The adjusting nut 70 is threadably connected to the cutter spindle 1 and serves to prevent longitudinal movement of the spindle with respect to the bearing 21. In this regard it will be noted the head 67 of the spindle is disposed on one side of the steel plate 63 and the nut 70 is disposed upon the opposite side of said hardened steel plate. The hardened steel plate 63, as above set forth, is secured to the bearing frame 49 by means of the screw 64.

The adjusting nut 70 is located at the end of the bearing 21 which is adjacent to the hob or cutter 71. The adjusting nut is so positioned in order to prevent the elongation of the spindle by reason of heat from changing the end-fit thereof. The bearings for the cutter spindle must be adjusted very snugly and, by reason thereof, and because of the heat flowing from the cutter, the temperature of the cutter spindle will rise during the operation of the machine. The portion of the cutter spindle included between the nut 70 and the hob 71 is very short. Accordingly, the effect on the work when the spindle is elongated or expanded by heat is negligible.

A plate 72 is provided for covering the opening in the main spindle bearing 21 and is secured in position by set screws 73. The plate 72 can be easily removed whenever it is desired to adjust the nut 70 for changing the position of the bushing 52 in the bearing frame 49.

The hob or cutter 71 is keyed on the cutter spindle 1 adjacent to a collar 74 and is held in position by means of nut 75. The worm wheel 4, which rotates the cutter spindle 1, is preferably composed of bronze and for such reason may better be indirectly connected to the spindle. As shown in Fig. 5 of the drawings, the worm wheel 4 is secured to a steel plate 78. The steel plate 78 is provided with a hub portion 79 which is splined to the spindle 1 and which projects through a bearing 80. A nut 81, which is threadably connected to the end of the hub portion 79, engages a balance wheel 82 for holding the steel plate 78 and the parts connected thereto against longitudinal movement with respect to the bearing 80. The cutter spindle 1, as above set forth, has a splined connection with the hub portion 79 and the balance wheel 82 is keyed to such hub portion.

The bearing 22 at the opposite end of the cutter spindle 1 comprises a bearing frame 84 having a bronze bushing 85 mounted therein. The bronze bushing 85 has a conical fit with the bearing frame 84 and has a cylindrical fit (to maintain concentricity and yet permit axial shifting) with a hardened steel sleeve 86 on the spindle 1. The hard-

ened steel sleeve 86 is preferably shrunk upon the spindle 1. The bronze bushing 85 is provided with a longitudinal slot therein in accordance with the usual practise to permit such bushing to adjust itself to various longitudinal positions with respect to the bearing frame 84 and the hardened bushing 86. The longitudinal position of the bronze bushing 85 is controlled by means of an adjusting nut 87 which is similar in construction to the adjusting nuts heretofore described for varying the longitudinal positions of the bushings in the various bearings. The nut 87 is threadably connected to the bronze bushing 85 and is positioned within a recess 88 formed in the bearing frame 84. A plate 89, which is secured to the frame 84 is provided for holding the nut 87 within the recess 88.

20 In Fig. 7 of the drawings is disclosed means for positioning the hob or cutter 71 with respect to the work. Such means comprises a short shaft 95 which is rotatably supported by the plate 47. Gear teeth 96 are formed on the lower end of the shaft for engaging the teeth of a rack 97 on the bearing frame 49. The shaft 95 has tooth-notches formed in its upper end and these engage with a worm (indicated as a dotted square in Fig. 7) on the shaft turned by the hand-lever 98; this being for the purpose of manually effecting longitudinal movement of the cutter spindle 1 and the hob 71 carried thereby. The bearing 22 is secured to the plate 47 by means of straps 100 and bolts 101.

Without further analysis, the foregoing will so fully reveal the gist of this invention that others can, by applying current knowledge, readily adapt it for various utilizations by retaining one or more of the features that, from the standpoint of the prior art, fairly constitute essential characteristics of either the generic or specific aspects 45 of this invention and, therefore, such adaptations should be, and are intended to be, comprehended within the meaning and range of equivalency of the following claims.

Having thus revealed this invention, I 50 claim as new and desire to secure the following combinations and elements, or equivalents thereof, by Letters Patent of the United States:

1. In a hobbing machine, the combination 55 comprising a cutter spindle having a cutter mounted thereon; a bearing for said cutter spindle; a manual control for translating said bearing; a work spindle rotated in timed relation to the rotation of said cutter spindle; a bearing for supporting said work spindle; adjustable means for restricting the end play of the cutter spindle for preventing longitudinal movement thereof with respect to the bearing for the cutter spindle; 60 means other than said adjustable means for

varying the diametral fit of the bearing with the cutter spindle; and other means for varying the fit of the work spindle bearing with the work spindle.

2. In a hobbing machine, the combination 70 comprising a cutter spindle having a cutter mounted thereon; a bearing for supporting the cutter spindle; adjustable means for controlling the diametral fit of the bearing with said spindle, said means being adjustable when the cutter spindle is in rotation; a work spindle rotated in timed relation to the rotation of the cutter spindle; a bearing for said work spindle; and variable means for controlling the diametral fit 75 of the work spindle bearing with the work spindle, said variable means being operative when the work spindle is in rotation.

3. In a hobbing machine, the combination 80 comprising a cutter spindle having a cutter mounted thereon; a work spindle; means for rotating and relatively translating said spindles in timed relation to each other; a horizontal bearing for supporting said cutter spindle; a vertical bearing for said work spindle; variable means for adjusting the cutter spindle bearing co-axially to fit the cutter spindle; means other than said variable means for preventing longitudinal movement of the cutter spindle with respect to the cutter spindle bearing; and two other means for adjusting the end fit 90 of the work spindle and the diametral fit of the work spindle bearing to the work spindle.

4. In a hobbing machine, the combination 95 comprising a cutter spindle having a cutter mounted thereon; a work spindle; means for rotating and relatively translating said spindles in timed relation to each other; a horizontal bearing for supporting said cutter spindle; a vertical bearing for said work spindle; means carried by the cutter spindle and connected to the cutter spindle bearing for adjusting the end fit of the cutter spindle; means carried by the cutter spindle bearing for adjusting the diametral fit between the cutter spindle and its bearing; and two means for adjusting the end fit of the work spindle and the fit of the work 100 spindle bearing to the work spindle.

5. In a hobbing machine, the combination 105 comprising a cutter spindle having a cutter mounted thereon; a bearing for supporting the cutter spindle and having a movable member provided with a conical surface for engaging a conical surface on the spindle; means operable when the spindle is rotating to shift said member to establish a diametral fit with the cutter spindle; a work spindle; a bearing for said work spindle and having a movable member provided with a conical surface for engaging a conical surface on the work spindle; and means for shifting the member on the work spindle 110

bearing when the work spindle is rotating.

6. In a hobbing machine, the combination comprising a cutter spindle having a cutter mounted thereon; a bearing for said cutter spindle; a work spindle rotated in timed relation to the rotation of said cutter spindle; a bearing for supporting said work spindle; adjustable means for limiting the end play of the cutter spindle and for preventing longitudinal movement thereof with respect to its bearing; means other than said adjustable means for varying the diametral fit of the bearing with the cutter spindle; variable means for limiting the end play of the work spindle for preventing longitudinal movement thereof with respect to its bearing; and means independent of said variable means and operative irrespective of the operative condition of the work spindle for varying the diametral fit of the work spindle bearing with respect to the work spindle.

7. In a hobbing machine, the combination comprising a cutter spindle having a cutter mounted thereon; a bearing for said cutter spindle; a work spindle rotated in timed relation to the rotation of said cutter spindle; a bearing for supporting said work spindle; adjustable means for limiting the end play of the cutter spindle for preventing longitudinal movement thereof with respect to its bearing; means other than said adjustable means for varying the fit of the bearing with the cutter spindle; and means for varying the fit of the work-spindle bearing to the work spindle and for varying the end fit of the work spindle bearing.

8. In a hobbing machine, the combination comprising a cutter spindle having a cutter mounted thereon; a bearing for supporting the cutter spindle; a work spindle rotated in timed relation to the rotation of the cutter spindle; a bearing for supporting the work spindle; means adjustable when the work spindle is rotating to fit the work spindle bearing diametrically to the work spindle; adjustable means for preventing longitudinal movement of the work spindle with respect to its bearing; means adjustable when the cutter spindle is rotating to fit the cutter spindle bearing diametrically to the cutter spindle; and means comprising a member threaded to the cutter spindle and positioned by the cutter-spindle bearing at the end adjacent to the cutter for preventing longitudinal movement of the cutter spindle.

9. In a hobbing machine, the combination comprising a cutter spindle having a cutter mounted thereon; a bearing for supporting the cutter spindle; a work spindle rotated in timed relation to the rotation of the cutter spindle; a bearing for supporting the work spindle; means comprising a member threaded to the cutter spindle and positioned by the cutter-spindle bearing at the end adja-

cent to the cutter for preventing longitudinal movement of the cutter spindle; and adjustable means for preventing longitudinal movement of the work spindle with respect to the bearing for the work spindle.

10. In a hobbing machine, the combination comprising a cutter spindle having a cutter mounted thereon; a bearing for supporting the cutter spindle; a work spindle rotated in timed relation to the rotation of the cutter spindle; a bearing for supporting the work spindle; means comprising a part rotatable as a unit with the cutter spindle and coacting with the cutter-spindle bearing at a point adjacent to the cutter for preventing longitudinal movement of the cutter spindle; adjustable means for preventing longitudinal movement of the work spindle with respect to the bearing for the work spindle; and means adjustable when the cutter spindle is in rotation to fit the cutter spindle bearing diametrically to the cutter-spindle.

11. In a hobbing machine, the combination comprising a cutter spindle having a cutter mounted thereon; a bearing for supporting the cutter spindle; adjustable means for controlling the diametrical fit of the bearing with said spindle, said means being operable when the cutter is in rotation; means comprising a member on the spindle for holding the spindle against longitudinal movement with respect to the bearing to control the cutter spindle end fit; a work spindle rotated in timed relation to the rotation of the cutter spindle; a bearing for said work spindle; and means comprising a member on the work spindle for holding the work spindle against longitudinal movement with respect to the work spindle bearing.

12. In a hobbing machine, the combination comprising a cutter spindle having a cutter mounted thereon; a bearing for supporting the cutter spindle; means for regulating the diametrical fit of the bearing with the cutter spindle; other means comprising a member shiftable on the spindle for holding the spindle against longitudinal movement with respect to the bearing; a work spindle rotated in timed relation to the rotation of the cutter spindle; a bearing for supporting the work spindle; means for controlling the fit of the work spindle bearing with the work spindle; and means comprising a member threaded to the work spindle for holding the work spindle against longitudinal movement with respect to its bearing to control the work spindle end fit.

13. A machine-tool combining a cutter spindle having a cutter mounted thereon; a bearing for said cutter spindle; adjustable means entirely located closely adjacent to said cutter for limiting the end play of the cutter spindle for preventing longitudinal movement thereof with respect to its bear-

ing; and means for varying the diametral fit of the cutter spindle bearing with the spindle.

14. A machine-tool combining a cutter spindle having a cutter mounted thereon; a work spindle rotated in timed relation to the rotation of said cutter spindle; a bearing for said work spindle; means having an adjustable member located near one end of the work spindle for limiting the longitudinal movement thereof; and means located near the opposite end of the work spindle for adjusting the diametral fit of the bearing with the work spindle.

15. A machine-tool combining a cutter spindle; a work spindle rotated in timed relation to the rotation of the cutter spindle; a bearing for said work spindle; adjustable means for varying the fit of the bearing with the work spindle; and other means for limiting the longitudinal movement of the work spindle with respect to the bearing.

16. A machine-tool combining a cutter spindle having a cutter mounted thereon; a work spindle rotated in timed relation to the rotation of said cutter spindle; a bearing for said work spindle; said bearing having a non-rotatable bushing provided with a conical surface for engaging the work spindle; means comprising an annular member threadably connected to said bushing for translating it to regulate the diametral fit of the bearing with the work spindle; and means comprising a second annular member threadably connected to the work spindle and secured to the bearing for limiting the longitudinal movement of the work spindle with respect to its bearing.

17. A machine-tool combining a cutter spindle having a cutter mounted thereon; a work spindle rotated in timed relation to the rotation of said cutter spindle; a bearing for said work spindle, said bearing having bushing provided with a conical surface for engaging the work spindle; means comprising an annular member threadably connected to said bushing and located near one end of the work spindle for varying the diametral fit of the bearing with the work spindle; and other means comprising a second annular member threadably connected to the work spindle near the opposite end thereof and connected to the bearing for preventing longitudinal movement of the work spindle with respect to the bearing.

18. A machine-tool combining a cutter spindle having a cutter mounted thereon; a bearing for said cutter spindle; adjustable means located adjacent to said cutter for regulating the extent of axial movement of the spindle; and means other than said adjustable means for adjusting the fit of said bearing to the spindle.

19. A machine-tool combining a cutter spindle having a cutter mounted thereon;

a bearing for said spindle; adjustable means connected to the bearing adjacent to said cutter for preventing axial movement of the spindle; and means other than said adjustable means for adjusting the fit of said bearing to the spindle and comprising a member rotatably supported by said bearing.

20. A machine-tool combining a spindle; a bearing for supporting said spindle; adjustable means for regulating the size of the bore of the bearing and adjustable when the spindle is in rotation; and means other than said bearing comprising a member threaded to the spindle for holding the spindle against longitudinal movement in said bearing.

21. A machine-tool combining a spindle; a bearing frame, a bushing for supporting the spindle in said bearing frame, said bushing having a cylindrical fit with said bearing frame and a conical fit with said spindle; means comprising a normally stationary member threadably connected to said bushing and rotatably restrained by said frame against any side shift for axially adjusting the bushing with respect to the spindle; and means mounted on the bearing frame for turning said member.

22. A machine-tool combining a cutter spindle having a cutter mounted thereon; a bearing frame; a non-rotatable bushing for supporting the cutter spindle in said bearing frame, said bushing having a cylindrical fit with said bearing frame and a conical fit with said cutter spindle; an annular member rotatably supported in said bearing frame and threadably connected to said bushing for adjusting the bushing longitudinally with respect to the spindle.

23. A machine-tool combining a cutter spindle having a cutter mounted thereon; a bearing for supporting the cutter spindle; and a nut threadably connected to said spindle and supported in said bearing so as to permit rotation and to insure against movement of translation, said nut being connected to the bearing adjacent to the cutter to prevent substantial displacement of the cutter by reason of heating the cutter spindle.

24. A machine-tool combining a cutter spindle having a cutter mounted thereon; a bearing frame; a bushing for supporting the spindle in the frame, said bushing having a cylindrical fit with said bearing frame and a conical fit with said cutter spindle; and two annular members supported in said bearing frame for respectively controlling the end fit of the spindle and the fit between said bushing and the spindle, one of said annular members being threadably connected to the bushing and the other annular member being threadably connected to said spindle.

25. A machine-tool combining a cutter spindle having a cutter mounted thereon; a

bearing for supporting said spindle; adjustable means for controlling the fit of the bearing with said spindle, said means being adjustable when the spindle is in rotation; 5 and means other than said adjustable means for preventing longitudinal movement of the spindle with respect to the bearing to control the spindle end fit.

26. A machine-tool combining a cutter 10 spindle having a cutter mounted thereon; a bearing frame; a bushing for supporting the cutter spindle in said bearing frame, said bushing having a cylindrical fit with said bearing frame and a conical fit with 15 said cutter spindle; adjustable means for preventing longitudinal movement of the spindle in said bearing frame; and means for adjusting the longitudinal position of the bushing in said bearing frame, said 20 means comprising a member rotatably located by the bearing frame and threadably connected to said bushing.

27. A machine-tool combining a cutter 25 spindle having a cutter mounted thereon; a bearing frame; a bushing for supporting the cutter spindle in said bearing frame,

said bushing having a cylindrical fit with said bearing frame and a conical fit with 30 said cutter spindle; adjustable means comprising a member threadably connected to the spindle and rotatably positioned by the bearing frame for preventing longitudinal movement of the spindle in said bearing; and means for adjusting the longitudinal position of the bushing in said bearing 35 frame, said means comprising a member rotatably supported by the bearing frame and threadably connected to said bushing.

28. A machine-tool combining a cutter 40 spindle having a cutter mounted thereon; a bearing for centrally supporting the cutter spindle; a nut threadably connected to said spindle at the end of the bearing adjacent to 45 said cutter; a shoulder formed on the spindle between said nut and the cutter; and a fixed plate located near said cutter and adapted to be clamped between the nut and said shoulder to prevent axial movement of the spindle.

In witness whereof, I have hereunto subscribed my name.

WILLIAM F. ZIMMERMANN.
